UNITED STATES PATENT OFFICE

CLARENCE P. BYRNES, OF SEWICKLEY, PENNSYLVANIA

VALVE FOR FURNACE REGENERATIVE CHAMBERS

Original application filed December 30, 1921, Serial No. 525,853. Divided and this application filed June 27, 1928. Serial No. 288,677.

This invention relates to valves for furnace regenerative chambers, and particularly to a valve of the sliding type. This application is a division of my copending application 5 Serial No. 525,853, filed December 30th, 1921.

Valves for regenerative chambers must be of relatively simple structure, and must be free from warping, and must retain their shape under adverse temperature conditions 10 so as to remain reasonably gas-tight at all times. I provide a valve comprising a seat and a valve member fitting thereon. The valve member comprises a metal skeleton or frame which is preferably water-cooled. 15 This skeleton or frame forms the seat engaging portion of the valve member, and by reason of the water cooling, it is maintained free from warping. The water-cooling also eliminates the tendency of the frame to cut 20 away when it is slid on the valve seat. Such tendency is very marked when the metal is hot.

The frame or skeleton of the valve member is filled in with refractory material, thus 25 forming a relatively inexpensive and durable construction. The metallic frame of the valve member is preferably made with a wrought portion adapted to form a water conduit and a metal portion cast about it, 30 which stiffens and reinforces the wrought metal portion and is shaped to receive the refractory material. The wrought metal portion may be a hollow frame of special shape and made, for example, from steel 35 plates welded together, or it may be made of wrought metal pipe. In either case there is provided a water space which may be tested before the cast metal portion is formed there-around.

40 In the accompanying drawings illustrating the present preferred embodiment of the invention and certain modifications thereof,

Figure 1 is a vertical section through a regenerative chamber having my improved 45 valve applied thereto,

Figure 2 is a top plan view of the valve member,

Figure 3 is a vertical longitudinal section taken on the line III-III of Figure 2,

50 Figure 4 is a perspective view of the

wrought metal portion of the frame or skeleton,

Figure 5 is a top plan view of the valve seat,

Figure 6 is a view corresponding to Figure 55 2 but showing a modified form of valve,

Figure 7 is a vertical transverse section taken on the line VII-VII of Figure 6, and

Figure 8 is a vertical transverse section taken on the line VIII-VIII of Figure 6. 60

Figure 1 shows a regenerative chamber 2 of any desired type, provided with valves 3 and 4 for controlling the passage of gases therethrough. It will be understood that the regenerator chamber is connected to the furnace through slag pockets and necks of any 65 well-known character.

Each of the valves 3 and 4 works on a valve seat 5. An opening 6 is provided in the wall of the passage controlled by the valve, 70 and a housing 7 for the valve and a part of its seat is formed outside the passage adjacent the opening 6. This provides space for the valve when it is in its open position and makes a substantially leak-proof construction. 75

Each of the valves 3 and 4 comprises a metal frame having a hollow wrought metal portion 8 and a cast portion 9, and a refractory portion 10 which is made arch-like and 80 fills the opening in the metal frame. The wrought metal portion 8 is made of welded plates and is shaped as shown in Figure 4 so as to avoid steam pockets. It is provided with clips 11 to receive an actuating rod 12. 85 The rod 12 extends through an opening formed in the end of the housing 7 and is connected through an operating cylinder (not shown).

The member 8 is provided with a connection 13 to receive a pipe 14. An interior pipe 1 extends through the pipe 14 and is connected to a supply of cooling water. The pipe 15 extends through the hollow member 8 and terminates at a point remote from the 95 connection 13 so as to insure a circulation of cooling water. The spent water is taken off thru the pipe 14 and a connection 16.

The cast metal portion 9 is preferably 100 poured around the wrought metal portion 8

and has its interior walls inclined as shown at 17 to form a proper foundation for the arch of the refractory material 10.

The valve seat is shown in detail in Figure 5. It comprises a casting 18 having a water cooling pipe 19 cast therein. The casting is provided with extensions 20 which support the valve when it is slid into its open position.

10 Figures 6 to 8 inclusive show a modified form of valve wherein a cast metal frame 9a has a wrought metal pipe 21 embedded therein to provide for the circulation of cooling water. The frame 9a carries a tongue 22 lying in a sleeve 23. Spaced holes are bored in the tongue 22 and the sleeve 23 and the parts are connected by a loose pin 24. This permits of adjusting the position of the valve relative to its operating rod 25 so that 15 the open or closed position of the valve may be varied as desired.

15 I preferably also form the valve, as shown in Figure 3, wherein the right hand portion of the hollow metallic frame is of less height than the left hand, thus avoiding the formation of steam pockets. A vent may be provided in the highest or deepest portion of the cavity to allow venting of any steam formed.

20 No claim is made herein to the regenerator system or method of operating single surface regenerators, such claims being embodied in my copending application Ser. No. 500,002, filed December 4, 1930, as a continuation in 25 part of application Ser. No. 525,853, filed December 30, 1921.

25 While I have illustrated and described a preferred form of the invention, it will be understood that it is not thus limited, but may be otherwise embodied within the scope 30 of the following claims.

I claim:

1. In a valve system for hot gases, a horizontally extending metallic seat surrounding a passage and having an enclosed passage therein for cooling fluid, connections for circulating a cooling fluid therethrough, a horizontally extending valve cooperating with said seat and subject to hot gases on its upper face, said valve having a surrounding metallic frame with a central opening therethrough, said frame having an enclosed passage for 45 cooling fluid, refractory material filling the central opening, and connections for circulating water through the passage in the surrounding valve frame.

2. In a valve system for hot gases, a horizontally extending metallic seat surrounding a passage and having an enclosed passage therein for cooling fluid, connections for circulating a cooling fluid therethrough, a horizontally extending valve cooperating with said seat and subject to hot gases on its upper face, said valve having a surrounding metallic frame with a central opening therethrough, 50 said frame having an enclosed passage for

cooling fluid provided with a higher portion arranged to discharge any steam formed therein, refractory material filling the central opening, and connections for circulating water through the passage in the surrounding valve frame. 55

In testimony whereof I have hereunto set my hand.

CLARENCE P. BYRNES.
